FOREIGN PATENT DOCUMENTS

KR 300751936.0000 7/2014

Primary Examiner — Marianne Pandozzi

Assistant Examiner — Jae Liang

CLAIM

The ornamental design for a bottle, as shown and described.

DESCRIPTION

FIG. 1 is a top, front, right perspective view of a bottle showing our new design;

FIG. 2 is a front view thereof; the rear view being a mirror image thereof;

FIG. 3 is a right side view thereof; the left side view being a mirror image thereof; and,

FIG. 4 is a top view thereof.
